Specification of Letters Patent. Patented Nov. 12, 1912.

Application filed December 29, 1911. Serial No. 668,390.

To all whom it may concern:

Be it known that we, WALTER S. NEWHALL, SCOTT W. LINN, and ALVA C. HEZLEP, residing at Cleveland, in the county of Cuyahoga and State of Ohio, have invented a certain new and useful Improvement in Thawing Apparatus, of which the following is a full, clear, and exact description, reference being had to the accompanying drawings.

10 The object of this invention is to provide an efficient apparatus for quickly thawing material in freight cars,—the invention being well adapted for thawing various kinds of material transported in cars, as, for example, coal, ore, or other material liable to freeze.

Our apparatus comprises a house or building provided with tracks in which cars of material to be thawed may be run, and 20 suitable means for heating air and giving it a forced circulation through the building and in contact with the cars and contents.

In carrying out the invention we have devised a long building or shed having 25 tracks and provided with closing doors at its ends and with insulating walls and roof, and we have provided a blower, a heater and air ducts so arranged that air is circulated throughout the building and reheated in its passage. We provide the main outgoing and return air ducts in the space between the roof and an underlying ceiling, the outgoing duct being continued downwardly by a series of vertical ducts along 30 the walls which discharge the air near the bottom of the cars, the return duct being in communication with the upper portion of the room below the ceiling. We have arranged the blower house or houses in the 35 upper part of the building, wherefore the blowers may communicate directly with the space between the roof and ceiling. These various features, as well as novel details in carrying out the same, including the arrangements of the ducts and the insulation, 40 are included within our invention.

Accordingly, our invention may be most conveniently summarized as consisting of the combinations of parts herein illustrated 45 and described and set out particularly in the claims.

In the drawings, Figure 1 is a vertical cross section through the heating shed. Fig. 2 is a similar cross section through the shed

at one of the blower houses. The planes of 55 these sections are indicated for example by the lines 1—1 and 2—2, respectively, in Fig. 5. Fig. 3 is a vertical longitudinal section through the blower house. Fig. 4 is a sectional plan of the blower house. Fig. 5 is 60 a side elevation of the thawing building. The remaining figures are sectional details, Fig. 6 being a view through one of the outer walls; Fig. 7 a section through the intermediate or central wall shown; Fig. 8 a 65 section through the other outer wall; Fig. 9 a section through the ceiling; and Fig. 10 a section through the roof. Figs. 6, 7, and 8, taken together, are in the nature of a horizontal section through the building, with 70 the size of the walls out of proportion to the space between them.

We divide our building longitudinally by one or more intermediate walls, so that 75 separate compartments are provided for each train of cars and the heat is supplied and circulated through each compartment individually. This allows the cars to be run in or out one portion of the building independently of the other and enables, moreover, the supplying of air on both sides of each train. In the embodiment shown we have provided a house for two tracks, so that there is an intermediate wall dividing the shed into two longitudinal compartments. In each compartment there is a trackway designated 1 and adapted to support a train of several cars designated 2. 80

Referring to Fig. 5, it will be seen that our building, in the embodiment shown, 90 consists of a long, narrow structure having a side wall 10, and a roof 11,—the roof being interrupted at one or more points by blower houses 13, two of these houses being shown in the drawing. The machinery in 95 each blower house 13 is designed to supply the hot air from the adjacent end of the building to the middle. It will, of course, be understood that, for longer buildings, more blower houses will be employed, while, 100 for the shorter building, one house might be sufficient. The end doors which may conveniently slide on past each other, are indicated at 12 in this figure.

The general construction of the building 105 is indicated in Fig. 1, and the details in Figs. 6 to 10. As shown in these views, the skeleton of the building consists of sills,

studs, purlins, joists and rafters. 15 and 15 indicate the outer sills and 16 the center sill. 20 indicates the studs for the outside walls and 22 the intermediate studs, these 5 studs resting on the sills. These studs carry cross girders 23 at the ceiling and rafters 24 at the roof. Suitable purlins 17, 17 and 18 hold the studs at their upper ends and support the rafters. This skeleton construction, in itself, is a usual one in frame buildings. We avail ourselves of it, however, to carry the insulation in the walls and roof, as hereinafter described.

We complete the outer walls and insulate them by securing on the outside of the studs 15 20 sheets of compressed hair within water proof paper designated 30, and, outside of this, suitable siding 31, and on the inner face of these studs 20 we secure tongue and 20 groove sheeting 32, and on the inner face of this, water proof paper, and on the inner side of this paper, sheets of plaster board 33 or other suitable material. We fill the space between the studs 20 with insulating material, as granulated cork, or other suitable 25 substance 35. By the means described, we have provided a very tight insulating wall within the main wall necessary to support the roof, and without unduly enlarging it.

30 In the interior or center wall it is sufficient to provide tongue and groove sheeting 37 on opposite sides of the studs 22, and fill the space between the studs with ground cork or other insulating material 35. In 35 the ceiling, we secure tongue and groove sheeting 39 above and below the joists 23, and on the upper and under faces respectively of the top and bottom sheetings we provide first water proof paper, which is then covered with plaster board 40, or other 40 suitable material. In the roof we provide below the rafters 24 tongue and groove sheeting 43 with water-proof paper and plaster board 44 below it, while above we provide 45 sheets of compressed hair 45 within water proof paper surmounted by roof boards 46, and above them a composition roof 47. Between the rafters we provide our usual filling material of cork or similar substance 35.

50 It will be seen from the above description that the walls and roof are thoroughly insulated internally, granulated cork, with its entrained air spaces, making a very satisfactory insulation. Furthermore, at the 55 parts exposed to the outside weather, namely, the outer sides of the walls and the roof, we have provided, just inside the outer member, the sheets of compressed hair which makes a further insulation. This construction is not only efficient but very economical.

We avail ourselves of the space between the ceiling and roof for the air ducts to and from the heater and blower system. As shown, this upper space, on each side of the 65 central wall, is divided into three longi-

tudinal flues by means of the two vertical partitions 50 and 51. The center flues 52, thus provided between the partitions 50 and 51, are designed to receive the air rising from around the cars through openings 55 70 in the ceiling and return such air to the blower. The air duct 53 between the partition 50 and the center wall, and the duct 54 between the partition 51 and the outside wall, carry the hot air, which is conducted 75 lengthwise of the building and at suitable intervals downwardly along the respective walls and discharged near the bottom of the cars.

For conducting the air downwardly from 80 the main ducts, we provide a large number of vertical discharge ducts located on the inner faces of the outer walls and on both faces of the intermediate wall or walls. We make these ducts by means of supplemental studs or vertical strips (designated 57 and 58 respectively) secured to the inner faces of the walls, and sheets of material, preferably fire proof, as for example, plaster boards 59 and 60 secured to the other edges of 85 these strips. Each of the supplemental studs is preferably surrounded by plaster boards 61. Accordingly, vertical flues 62, 62 and 63, 63 with heat-resisting walls or lining are provided serving to conduct the 90 hot air downwardly from the flues 53 and 54. These vertical flues are open at their 95 lower portions toward the trackway by the omission of the inner plaster boards at such points, as indicated in Fig. 1.

100 With the construction described, hot air blown through the flues 53 and 54 passes downwardly through the flues 62 and 63 and discharges beneath the car bodies, and rising around the same and passing over the tops of the cars and discharging through the openings 55 in the ceiling, effectively thaws the contents of the cars. The amount of air delivered may easily be regulated by shutting off some of the vertical flues by laying 110 boards across their upper ends.

Suitable drain pipes are provided for conducting away the water resulting from the thawing of the contents. These pipes are preferably soft tiles, and laid through the 115 entire length of the building, alongside of the trackway. These are designated 66 in Figs. 1 and 2.

120 It now remains to describe the blower houses and the blowing apparatus which receives the air through the intermediate ducts 52 and returns it, heated, through the ducts 53 and 54. We have shown two blower houses 13 intermediately located. Each house has its floor just above the ceiling through the shed, so that the bottom portion of the blower room interrupts, and may communicate directly with the horizontal flues 52, 53 and 54. One of the blower houses is shown in cross section in Fig. 2, 130

and it is to be understood that this is illustrative of any of the blower houses.

At the blower houses, the outside studs 20 and the intermediate stud 22 are provided at their tops with longitudinal beams or purlins 70 and 71 which support the joists, preferably in the form of steel I-beams 72, and above these I-beams is a suitable flooring 73 of beams laid on edge. This makes a firm floor for the machinery. Above the floor the walls are continued by the outside studs 75, and intermediate studs 76, and are connected at their upper ends by the ceiling joists 77 and the rafters 78. Suitable internal and external facings and insulating fillings are provided for the walls, as well as for the roof to properly retain the heat in the blower rooms. Details of this construction may be similar to that heretofore described for the train shed proper and will not be here repeated.

Within each blower room is a suitable blower of any approved type. The blower shown is a centrifugal fan having a casing 80 with a central intake 82 and a tangential discharge. The fan within the blower casing is mounted on a suitable central shaft 81 and is suitably coupled with the engine 83, or other driving means. The tangential discharge end 85 of the blower casing is connected by a flaring hood 86 with a heater casing or plenum chamber 87 in which are suitable coils 88 of steam pipe. These coils are not fully shown because they may be arranged in any desired manner, but it is to be understood that there are a sufficient number of them within the casing 87 to provide an effective radiator to heat the air discharged by the fan. Some of these coils may receive exhaust steam from the engine 83 and others be heated from the live steam plant, or other means for supplying heat may be employed, as desired.

The discharge end of the heating casing 45 or plenum chamber 87 connects with the transverse duct 92 extending across the blower room near its ceiling. At the ends of this transverse duct are elbows 89 leading to the downtake flues 90 and intermediate there is a central downtake 95 divided by a vertical partition 96 in its lower portion into two parallel flues. The downtakes 90 discharge through the ports 91 in the end of the room into the hot air ducts 54, while 55 the downtakes 95 discharge into the two hot air ducts 53. The return air ducts 52 discharge into the end of the blower room, and such returned air is taken directly from the room into the blower, through the central 60 fan opening thereof, for example.

Provided in the several downtake ducts 90 and 95 mentioned are dampers 93, each adapted to vary or close the corresponding duct. These dampers are effective in enabling either half of the building to re-

ceive the entire supply of heated air from all the blowers and heaters, the appropriate positioning of the dampers directing all the air to one side or the other as selected. This enables concentration of heat should the same be desired in case of very severe freezing or for other cause. The dampers are also useful, when not fully closed, in regulating the force of the draft through the respective flues.

Windows 14 in the blower house provide for the admission of outside air thereto, as desired, to refresh the circulating air and maintain the proper temperature. A steam jet 99 discharging into the plenum chamber to keep the air properly moistened may be employed if desired. Doorways or other means, not shown, allow access to the blower rooms.

By means of regulating the steam pressure, the rotation of the fan, the draft and the admission of outside air, the hot air delivered may be regulated, as desired, and be thus maintained at a point high enough to be very effective without injuring the paint on the cars or doing other damage.

To provide for heating the train shed immediately below the blower house, we form suitable supplemental downtake flues 97 and 98 from the main downtakes 90, these downtakes 97 and 98 communicating with the outer and intermediate flues 62 and 63 which come beneath the blower house.

While we have shown two longitudinal train compartments in our building, it is to be understood that the number may be increased at will. In fact, Figs. 6 and 8 show one outside wall made thicker than the other, such thickening being for the purpose of enabling the wall of Fig. 8 to act as an intermediate wall in case it is desired to increase the capacity for forming an other compartment alongside of such wall.

In the operation of our apparatus, on or more doorways at the end of the shed are opened and a train of a number of cars are run in by gravity or motive power and the door is closed and the heating started. The heat entering the closely confined compartment around the train rapidly thaw the contents of the cars and the water liberated drains off through the drain. The air of reduced temperature returning to the blower house is reheated and again discharged into the heating room, and so on continuously. When the cars are thawed out the doors are opened and the cars removed, by gravity or otherwise.

The time required to thaw the contents of a train varies, of course, with the degree to which the contents is frozen, but, simply by way of illustration, it may be said that a car load of fifty tons of coal frozen solid may be thawed with this apparatus, sufficiently to be dumped, in two hours time.

By way of further illustration, we may note that we have found it efficient, in an equipment having double tracks, each track carrying thirteen cars, to provide the radiators with steam under one hundred and twenty-five pounds pressure, and each of the four blowers delivering 40,000 cubic feet of air per minute, the final temperature of the air from the heater being 250° Fahrenheit, the air delivered in the train rooms 200° and the air returned to the blower rooms 130°. These items, however, are given simply by way of illustration, and the invention is in no manner confined thereto.

Having thus described our invention, what we claim is:

1. In an apparatus of the class described, the combination of a building having walls, a roof, and a ceiling, outgoing and return air conduits located within the building between the roof and ceiling, downwardly extending flues carried on the inner face of the wall from said outgoing conduit, and means for establishing a forced circulation of air from the return conduit to the outgoing conduit, and means for heating such air.

2. In an apparatus of the class described, the combination, with a shed having walls and a roof, of two hot air conduits adjacent to the roof and to the walls respectively, and an intermediate return conduit adjacent to the roof, downwardly extending flues from the two hot air conduits to the bottom portion of the building, there being openings from the upper portion of the building into the return conduit, means for continuously circulating the air from the return conduit to the hot air conduits, and means for heating such air.

3. In an apparatus of the class described, the combination, with insulated walls and an insulated roof, of a ceiling between the walls and below the roof, conduits for the passage of air between the ceiling and roof, downward flues leading from such conduits to the bottom portion of the building, and means for circulating air continuously through such conduits.

4. The combination, with a trackway, of a building housing the same and comprising insulated walls and an insulated roof and a ceiling, downwardly extending flues along the opposite sides of the inner faces of the walls, said flues being open near their lower ends, two hot air ducts adjacent to the walls and between the roof and ceiling communicating with said flues, an intermediate return duct between the hot air ducts and in communication with the upper portion of the room below the ceiling, means for forcing the air returning through the return duct to the hot air ducts, and means for heating such air.

5. In a thawing apparatus, the combination, with a trackway, of a building housing

the same, outgoing and return air ducts within the building, the outgoing duct discharging near the bottom of the building and the return duct having intakes near the top of the building, a blower for forcing air from the return duct to the returned outgoing duct, means for heating the air, and a drain alongside of the trackway for carrying away the water with which the heat liberates from the material being thawed before its discharge into the trackway chamber.

6. The combination of a trackway, a compartment housing the same, horizontal hot air ducts in the upper part of such compartment adjacent to the outer walls, down-take ducts leading from the hot air duct and extending downwardly along the side walls of the building and open on their inner sides near the bottom, a return air duct communicating with the upper portion of the housing, and means for circulating the air continuously from the bottoms of the down-take flues across the cars to the return duct and from the return duct to the hot air ducts.

7. The combination of a long narrow compartment having a trackway and adapted to inclose several cars, closures for the ends of the compartment, air ducts located in the upper part of the compartment adjacent to the roof, down-take flues connected with those of the ducts which are for hot air, said flues being open on their inner sides near the bottoms, a return duct located adjacent to the roof and communicating with the upper portion of the room, a blower in a casing adapted to receive air from the return flue and force it across a heater in the hot air ducts, and means for controlling the admission of fresh air.

8. In an apparatus of the class described, the combination of a building providing a drying chamber having side walls and roof, insulating filling between the studs of the side walls and between the rafters of the roof, a hot air duct located along the under side of the roof, down-take flues located along the inner side of a wall, a means for heating air outside of the drying chamber and forcing it through the hot air duct and into the room through the down-take flues.

9. In an apparatus of the class described, the combination of a building having walls, a roof and a ceiling, the walls and roof being insulated by filling material placed between its respective studs and rafters, air flues located within the space between the ceiling and the roof and adjacent to the walls, a return duct between the hot air ducts and between the ceiling and roof, downwardly extending flues formed on the inner faces of the walls and communicating with the hot air ducts, said flues being open

near their lower ends, a heater, and a blower adapted to force air across the heater and into the hot air ducts.

10. In an apparatus of the class described, the combination of a wall composed of studing with sheeting on its opposite sides, insulating material in the space between the studs and between the sheeting, supplementary studs on the inner side of the inner sheeting, sheets secured to the inner side of the supplementary studs whereby flues are provided along the inner side of the wall, which flues are insulated by the material between the studs of the main wall, and means for forcing heated air through said flues.

11. In an apparatus of the class described, the combination of a train compartment, a railway track therein, hot air and return ducts above said compartment, a blower room above said compartment, the lower portion of said room being opposite the ends of the ducts referred to, and a blower in said room for forcing air through said ducts.

12. In an apparatus of the class described, the combination of a building having walls, a roof and a ceiling leaving a train compartment between the walls and below the ceiling, a blower room located above the ceiling and with its lower portion opposite the space between the roof and ceiling, air ducts in such space, and a heater and blower in the blower room communicating with the air ducts.

13. In an apparatus of the class described, the combination of a building having walls, a roof and a ceiling leaving a train compartment between the walls and below the ceiling, a blower room located above the ceiling and with its lower portion opposite the space between the roof and ceiling, air ducts in such space, a heater and blower in the blower room communicating with the air ducts, down-take flues on the inner faces of the walls communicating with the ducts into which the air is forced, said flues being open at their lower ends, and there being a return duct for the cooler air.

14. In an apparatus of the class described, the combination of a building having walls, a roof and a ceiling providing a train shed, a track in said shed, partitions dividing the space between the ceiling and roof into hot air and return ducts, a blower room located above the ceiling and intersecting the roof and having its lower portion in alinement with said hot air and return ducts, and a blower in said room receiving its air from the return duct and discharging it into a hot air duct.

15. In an apparatus of the class described, the combination of a building having walls, a roof and a ceiling, of separating partitions dividing the space between the ceiling

and roof into hot air and return ducts, a blower room located above the train compartments with its floor adjacent to the ceiling, the lower portion of the room opposite the ends of the said ducts, a blower in said room for receiving air from the return duct and returning it through the hot air duct, a heater for such air, and downward flues along the inner faces of the walls and open at their lower ends for discharging the heated air into the train room.

16. In an apparatus of the class described, the combination, with the side walls, roof and ceiling providing a train compartment between the walls and below the ceiling, air ducts between the ceiling and roof, downwardly extending flues along the side walls of the train compartment, a track within the train compartment adapted to carry cars in position to be heated by the air discharged from said flue, openings from the upper portion of the train compartment to the return flue, a blower house located at an intermediate portion of the building above the ceiling and with its lower portion opposite the ends of said flues, a heater in such blower house, a casing surrounding the heater and connecting with the hot air ducts, and a blower for receiving air from the return duct and blowing it across the heater to the hot air ducts.

17. In an apparatus of the class described, the combination of a train compartment, air ducts located adjacent to the roof of such compartment, a blower room above the compartment with its lower portion opposite the ends of the ducts, means for forcing air from said room into the ducts, means for heating such air, means for conveying such air downwardly at various points along the side walls of the building, and additional means for conveying air downwardly to portions of the train compartment beneath the blower room.

18. The combination of a long narrow building adapted to house a train of cars with walls on opposite sides of the track, a ceiling above such train and a roof above the ceiling, horizontal air ducts in the space between the roof and ceiling, vertical downwardly extending ducts along the inner faces of the walls leading from such air ducts and open near their lower ends into the train compartment, a blower room located above the ceiling and intersecting the roof, whereby the lower portion of the room aligns with the horizontal air ducts, a blower in said room for forcing air into said ducts, special air ducts extending downwardly from the main ducts at the blower room and extending lengthwise of the building beneath such room, and discharging downwardly.

19. In an apparatus of the class described, the combination of a plurality of train sheds

side by side, individual hot air and return ducts therein, a blowing device adapted to circulate such air in the individual train sheds, means for concentrating the action of the blowing device to any shed, and means for heating the air.

20. In an apparatus of the class described, the combination of two train sheds side by side, individual hot air and return ducts for each shed, a blowing apparatus connected with the ducts of both sheds, and dampers adapted to restrict the action of such apparatus to either shed.

21. In an apparatus of the class described, the combination of two train sheds side by side, each shed having adjacent to its roof a pair of hot air ducts and an intermediate return duct and having adjacent to its walls downtake flues connected with the hot air ducts, a blower room above the ceiling of the train shed and a pair of blowers in the blower room, conduits connecting the two blowers in opposite directions with the four hot air ducts mentioned, and dampers adapted to restrict the action of each blower to either train shed as desired.

22. In an apparatus of the class described, the combination of a train shed having

walls, roof and ceiling, a pair of hot air ducts located between the roof and ceiling adjacent to the walls, an intermediate return duct, an intermediately located blower room above the ceiling of the train shed, and a pair of blowers in said blower room discharging in opposite directions into the hot air ducts mentioned, said blowers being adapted to be fed by the air returned by the return ducts.

23. In an apparatus of the class described, the combination of a train shed, a blower room located at an intermediate point at the top of the train shed, a pair of blowers in said blower room discharging in opposite directions, means for conducting air from such blowers through the train shed and returning it to the blowers, and means for heating such air.

In testimony whereof, we hereunto affix our signatures in the presence of two witnesses.
